(57) **CLAIM**

The ornamental design for a safety belt, as shown and described.

DESCRIPTION

FIG. 1 is a front perspective view of a safety belt showing new design;

FIG. 2 is a front view thereof;

FIG. 3 is a rear view thereof;

FIG. 4 is a right side view thereof;

FIG. 5 is a bottom view thereof;

FIG. 6 is a top view thereof; and,

FIG. 7 is a rear perspective view thereof.

A left side view is omitted since the left view is a mirror image of the right side view.

1 Claim, 7 Drawing Sheets
